UNITED STATES PATENT OFFICE.

HARRY BUDD, OF INDEPENDENCE, KANSAS.

CLOTHES-WRINGER.

1,215,339.

Specification of Letters Patent. Patented Feb. 13, 1917.

Application filed April 12, 1915. Serial No. 20,727.

To all whom it may concern:

Be it known that I, HARRY BUDD, a citizen of the United States, residing at Independence, in the county of Montgomery and

5 State of Kansas, have invented certain new and useful Improvements in Clothes-Wringers; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to clothes wringers, and has for its principal object to provide a wringer which will effectively remove water from articles passed therethrough, and accomplishing this object by improved details 20 of structure comprising means for urging the ordinary horizontal wringer rollers toward each other and including vertical rollers for engaging the articles vertically at the ends of the horizontal rollers.

25 In the drawings wherein the preferred forms of structure are illustrated:

Figure I is a perspective view of a wringer constructed according to my invention and illustrating its use with a washing apparatus.

Fig. II is an elevation of the wringer.

Fig. III is a central cross section of the same.

Fig. IV is a sectional view of the upper 35 end of the side standards.

Fig. V is a horizontal section on the line V—V, Fig. III.

Fig. VI is a sectional view of the horizontal roller supports showing the tensioning means.

Referring more in detail to the drawings:

1 designates a device constructed according to my invention comprising side standards 2, which extend above the tub level to 5 form the side members of the wringer and carry a washing device 3.

Each of the side standards 2 is provided at the upper end with a vertical slot 4 and slidably mounted in said slots and adapted 0 for vertical travel therein are bearing blocks 5; the said blocks being provided with side guide lugs 6 which travel in channels 7 in

the slot faces, to retain the blocks in proper position.

Revolutely mounted in the bearings 5 are 55 the shafts 8 of wringer rollers 9 which are operated in the usual manner by means of a handle 10 and gears 11.

In order to tension the rollers toward each other I have provided, in each side standard, an upper and a lower coiled spring 12—13, the lower spring at each side being projected a greater part of its length within a vertically bored socket 14 extending from the bottom of the slot 4; the socket being 65 slightly greater in diameter than the spring contained therein, and having a port 15 at its base, so that water may be drained therefrom. The upper end of the spring 13 forms a yielding support for the bearing block 5 70 which carries the lower roller 9.

The upper tensioning spring 12 is seated on the upper bearing 5 and is tensioned thereagainst by a screw 15 which is threaded through the upper cross bar 16 and engages 75 a cross plate 17 against which the upper end of the spring 12 bears, so that the spring may be adjusted by manipulation of the screw.

As the articles fed to the wringer are 80 usually thicker at the center of the mass than at the edges, I provide for compressing the relatively thin edges to insure uniform wringing by equipping the wringer with a secondary set of rollers 20, which are supported horizontally within upper and lower 85 guide members 21 and 22.

The upper guide 21 preferably comprises a horizontal tube having end supports 24 by which it is secured to the side standards 2, 90 and having, in its under face near each end, elongated slots 25 within which is projected the axle 26 of a roller 20.

The lower support 22 comprises a short length of tubing, at each end of the wringer, 95 arranged so as not to interfere with articles passing into the wringer, and which is supported from the standards 2 in the same manner as the upper member; the members 22 having slots 27 in their upper faces for 100 receiving the lower end of the axles 26.

Within each of the tubular supports 22 is located a coil spring 28, which bears at one end against the closed outer end of the tube

and at the opposite end against an axle 26, so that the rollers are yieldingly tensioned toward each other and against the articles as they come from the wringer.

5 I also provide the device with gearing shields 30, which are slidably mounted over the gearings and provided with apertured arms 31, through which the upper springs 12 are projected.

10 It will be seen that with my improved construction, the efficiency of the wringer is increased by the increase of resiliency of the rollers, and that it is less apt to damage buttons, or the like, or to sustain damage itself than is a wringer having a single yieldable 15 roller.

Having thus described my invention, what I claim as new therein, and desire to secure by Letters-Patent, is:—

20 1. A wringer comprising a pair of wringer rollers, a second pair of rollers arranged crosswise of the first, and means for yieldingly urging the rollers in the second pair toward each other.

Copies of this patent may be obtained for five cents each, by addressing the "Commissioner of Patents, Washington, D. C."

2. A wringer comprising horizontal rollers, spaced supports arranged parallel to the horizontal rollers, rollers slidably mounted in said supports, and means for urging said rollers toward each other. 25

3. A wringer comprising horizontal rollers, means for yieldingly urging said rollers toward each other, spaced supports arranged parallel to the rollers, and having facing slots, rollers having end axles slidably mounted in said slot, and springs in said 30 supports engaging the axles to urge the rollers toward each other. 35

4. A wringer comprising horizontal rollers, spaced supports arranged parallel to the rollers, the lower of said supports being 40 formed in end sections to provide a space therebetween, and all of said supports being provided with longitudinal slots, rollers having axles projected into said slots, and springs in said supports engaging the axles 45 to urge the rollers toward each other.

In testimony whereof I affix my signature.

HARRY BUDD.
